UNITED STATES PATENT OFFICE.

IVER J. RIDER, OF PORTLAND, OREGON.

RADIATOR CAP.

Application filed November 19, 1923. Serial No. 675,701.

To all whom it may concern:

Be it known that I, IVER JAMES RIDER, a citizen of the United States, residing at Portland, in the county of Multnomah and

5 State of Oregon, have invented new and useful Improvements in Radiator Caps, of which the following is a specification.

The object of this invention is to provide a cap for the radiator of an automobile engine, which will not only close the threaded inlet connection or neck portion, but which will also provide for the display of a sign of any desired character, or will show the name of the city or State from which the 15 motorist comes.

A further object is to provide in modified forms, signs or name plates adapted to be secured to the cap, or to be held in position by screwing said cap down on the elements 20 specified and on the inlet connection.

With the foregoing and other objects in view, the invention consists in the novel construction and arrangement of elements described, illustrated and claimed, it being 25 understood that modifications may be made within the scope of the claim without departing from the spirit of the invention.

In the drawings, Figure 1 is an elevation of the device, mounted on a radiator; Figure 2 is a fragmentary view, in elevation, portions being broken away; Figure 3 is a section on line 3—3 of Figure 1; Figure 4 is a view of an illuminated casing, chiefly in elevation, but with a portion broken 35 away; Figure 5 is a section on line 5—5 of Figure 4; Figure 6 is a section on line 6—6 of Figure 4; Figure 7 is a vertical section showing a special form of connecting means between the sign and cap; Figure 8 shows 40 this arrangement in elevation and vertical section; Figure 9 is a fragmentary view of an externally threaded cap or plug; Figures 10 and 11, in top plan and elevation, respectively, show a sign having a ring member adapted to fit an inlet connection and to 45 be held by the cap.

The threaded inlet connection of a radiator is designated 10, and a combined cap and name plate, or sign, is shown at 12. This 50 element 12 may be ten or twelve inches long, and in the present instance is shown as being formed with raised letters showing the name of an important city and adapted to project from the cap in pennant form.

55 The bar or plate 12 extends in a horizontal position when mounted, the major portion

of its length being in the rear of the element 10, but the exact position is not important. Similar words or designations are usually carried on both sides.

The forward portion of bar or plate 12 includes an internally threaded portion 14 designed to cooperate with the threaded connection 10 and serve the usual function 60 of a cap.

In Figure 4 the word or sign to be displayed is carried on opposite sides of a casing 11, two inches or less in cross section, and having transparent walls, the casing being adapted to be illuminated by small electric lamps 15. Projecting within the casing is a threaded sleeve 16, closed at its upper end and open at the lower end, and therefore adapted to be screwed over element 10, in substantially the same position as in 70 the form first described.

It will be observed that element 16 is formed integrally with the casing and projects thereinto, and that the cuplike form prevents vapor from entering the casing. 80 More definitely element 16 forms an inverted cup.

In another form a separate plate 13 is secured to a standard type of cap 13'.

In a further form (Figure 9), I have 85 shown a plate 12' having formed therewith an enlargement 17 threaded and adapted to be screwed into an internally threaded neck.

The element carrying the display matter may however have formed thereon an annular internally threaded member or plain ring member 19 proportioned to fit the inlet connection 10, and to be surmounted by a radiator cap of normal or usual construction or form. In the views showing this 90 arrangement (Figures 10 and 11), the plate adapted to carry the letters is designated 12''. This is one of the most inexpensive forms, as the ring portion may be cut from the same flat plate of sheet metal as element 12'', and a twist formed at 19' in order that the ring portion and plate may be 95 perpendicular to each other.

What I claim is:

A sign formed as a casing, means for illuminating the casing, and an internally threaded element formed as an inverted cup, integral with the casing, and projecting thereinto, for engagement with the threaded inlet connection of a radiator.

In testimony whereof I affix my signature.
IVER J. RIDER.
